US0D1068325S

(12) United States Design Patent (10) Patent No.: US D1,068,325 S
(45) Date of Patent: * Apr. 1, 2025

(54) HANGING BAG

(71) Applicant: Yiwu Shitanli Industrial Product Design Co., Ltd., Jinhua (CN)

(72) Inventor: Yunchao Zhou, Jinhua (CN)

(73) Assignee: Yiwu Shitanli Industrial Product Design Co., Ltd., Jinhua (CN)

() Term: 15 Years

(21) Appl. No.: 29/970,104

(22) Filed: Oct. 25, 2024

(30) Foreign Application Priority Data

Sep. 9, 2024 (CN) 202430574577.8

(57) CLAIM

The ornamental design for a hanging bag, as shown and described.

DESCRIPTION

FIG. 1 is a perspective view of my new design, showing a hanging bag;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged partial view of a part enclosed 9 in FIG. 4;

FIG. 10 is an enlarged partial view of a part enclosed 10 in FIG. 5;

FIG. 11 is an enlarged partial view of a part enclosed 11 in FIG. 6; and,

FIG. 12 is an enlarged partial view of a part enclosed 12 in FIG. 7.

The line shading in FIGS. 1-12 represents contour and not surface ornamentation.

The broken lines in the figures indicate boundaries of enlarged views and form no part of the claimed design.

1 Claim, 12 Drawing Sheets
